(57) CLAIM

The ornamental design for a combined set of sofa, chairs, and tables, as shown and described.

DESCRIPTION

FIG. 1 is a perspective view of the combined state of a combined set of sofa, chairs, and tables, consisting of a chair, a side table, a sofa, a coffee table, and a swivel chair;
FIG. 2 is a bottom perspective view of the combined state thereof;

FIG. 3 is a front perspective view of the sofa component of the combined set of sofa, chairs, and tables of FIG. 1, shown separately to reveal aspects of the design that may not be apparent in other views;

FIG. 4 is a rear perspective view thereof;

FIG. 5 is a front view thereof;

FIG. 6 is a rear view thereof;

FIG. 7 is a left side view thereof;

FIG. 8 is a right side view thereof;

FIG. 9 is a top view thereof;

FIG. 10 is a bottom view thereof;

FIG. 11 is a front perspective view of a chair component of the combined set of sofa, chairs, and tables of FIG. 1, shown separately to reveal aspects of the design that may not be apparent in other views;

FIG. 12 is a rear perspective view thereof;

FIG. 13 is a front view thereof;

FIG. 14 is a rear view thereof;

FIG. 15 is a left side view thereof;

FIG. 16 is a right side view thereof;

FIG. 17 is a top view thereof;

FIG. 18 is a bottom view thereof;

FIG. 19 is a front perspective view of a swivel chair component of the combined set of sofa, chairs, and tables of FIG. 1, shown separately to reveal aspects of the design that may not be apparent in other views;

FIG. 20 is a rear perspective view thereof;

FIG. 21 is a front view thereof;

FIG. 22 is a rear view thereof;

FIG. 23 is a left side view thereof;
 FIG. 24 is a right side view thereof;
 FIG. 25 is a top view thereof;
 FIG. 26 is a bottom view thereof;
 FIG. 27 is a front perspective view of a side table component of the combined set of sofa, chairs, and tables of FIG. 1, shown separately to reveal aspects of the design that may not be apparent in other views;
 FIG. 28 is a rear perspective view thereof;
 FIG. 29 is a front view thereof;
 FIG. 30 is a rear view thereof;
 FIG. 31 is a left side view thereof;
 FIG. 32 is a right side view thereof;
 FIG. 33 is a top view thereof;
 FIG. 34 is a bottom view thereof;
 FIG. 35 is a front perspective view of a coffee table component of the combined set of sofa, chairs, and tables of FIG. 1, shown separately to reveal aspects of the design that may not be apparent in other views;
 FIG. 36 is a rear perspective view thereof;
 FIG. 37 is a front view thereof;
 FIG. 38 is a rear view thereof;
 FIG. 39 is a left side view thereof;
 FIG. 40 is a right side view thereof;
 FIG. 41 is a top view thereof; and,
 FIG. 42 is a bottom view.
